United States Patent Office

Des. 196,101
Patented Aug. 27, 1963

196,101

BUILDING

John P. Bittner, 9 Linden St., Brattleboro, Vt.

Filed July 19, 1961, Ser. No. 65,980

Term of patent 14 years

(Cl. D13—1)

FIG. 1 is a top perspective view of a building, showing my new design;

FIG. 2 is a top plan view thereof;

FIG. 3 is an elevational view looking from the top of FIG. 2; and

FIG. 4 is an elevational view thereof, looking from the bottom of FIG. 2.

The dominant features of my design reside in the portions shown in full lines.

I claim:

The ornamental design for a building, as shown and described.
